UNITED STATES PATENT OFFICE.

WILLIAM L. HANCOCK, OF DALLAS, TEXAS, ASSIGNOR TO THE MURRAY COMPANY, OF DALLAS, TEXAS, A CORPORATION OF TEXAS.

HULLER AND OPENER.

Application filed September 14, 1928. Serial No. 305,946.

This invention relates to new and useful improvements in hullers and openers.

The invention has to do with machines for cleaning seed cotton from burrs and hulls and picking the seed cotton therefrom; and involves certain improvements over the invention set forth in my Letters Patent No. 1,605,940, issued November 9, 1926.

One object of the invention is to provide in place of the wide single belt of my patent, a plurality of relatively narrow belts so closely associated as to produce as efficient a carrier as the single belt, but having the advantage of being individually replaceable, thus making for convenience and economy.

Another object of the invention is to provide a central feed for the incoming seed cotton in conjunction with lateral distribution to each side, whereby belts are maintained at each side for handling waste cotton and hulls, and an even distribution is had.

A further object of the invention is to provide exteriorly controlled means of an improved character for adjusting the chute aprons.

Still another object of the invention is to provide a machine which will handle the cotton without putting shale into the same and also whereby the long fibres will be preserved and the spinning value increased.

A construction designed to carry out the invention will be hereinafter described, together with other features of the invention.

The invention will be more readily understood from a reading of the following specification and by reference to the accompanying drawings in which an example of the invention is shown, and wherein:

Fig. 1 is a front elevation of a machine constructed in accordance with my invention,

Fig. 2 is a transverse vertical sectional view of the same,

Fig. 3 is a front view of the machine with the front wall removed,

Fig. 4 is a horizontal cross-sectional view taken on the line 4—4 of Fig. 1,

Figs. 5 and 6 are details of the belt structure,

Figs. 7 and 8 show in diagrammatic form the belting layout on opposite sides of the machine, and

Fig. 9 is a view of a group of the pulleys, one being shown in elevation and the others in section.

In the drawings the numeral 10 designates the main frame of the machine. This frame may be made of angle bars or suitable members and is of a general rectangular shape, extending vertically and smaller at the top than at the base.

One of the important features of the invention is the vertical carrier or belt member made up of a plurality of individual belts 11 placed in parallel order. The upper support for the belts is a drive shaft 12 on which flanged pulleys 13 are fastened, one pulley being provided for each belt. The belts also pass around flanged pulleys 14 mounted on a shaft 15. The shafts extend transversely of the frame at the top and bottom thereof and are suitably journaled. The pulley flanges 151 are of metal and are comparatively thin, but one being used between each pair of pulleys, thus permitting the vertical edges of the belts to travel in close relation.

The front stretch or reach of each belt travels upwardly in the direction of the arrow and the drive shaft 12 is offset from the shaft 15, whereby the belts are inclined. The upwardly moving reaches of the belts 11 are supported and backed up by a smooth slide or support 16, preferably formed of smooth vertical wooden strips or other suitable material. The function of this element is to back up and define with certainty the line of travel of the front reaches of the belts, preventing sagging and giving an unyielding reaction to the impact of the seed cotton.

The belts 11 are duplicates and a description of one will explain the structure of all. Each belt in its preferred form is covered with innumerable projecting wire teeth, imbedded in the substance of the belt, which belt may be of woven fabric or leather or rubberized canvas fabric. (See Figs. 5 and 6.) The wire teeth 1^x are preferably of tempered steel wire, bent and embedded in the belt material as is common in the fabrication of sheets of so-called card clothing, but my improved belt differs from these card-clothing sheets, not only in being a continuous belt, continuously covered with upstanding wire teeth, but also, in its best form, in being provided with back sheet 1^{xx} of fabric, cemented to the back of the belt and covering the exposed embedded end of the teeth as they appear upon the back of the 110

main belt sheet. This backing sheet has the effect of preventing the teeth from being forced backwards by the impact of foreign material in the seed cotton and adds to the 5 tensile strength and durability of the belt and its frictional grip upon its actuating pulley, so that it is moved steadily and smoothly. It is especially useful however, because the continual working and bending 10 of the belt in its passage over the pulleys or supports at each end, has a distinct tendency to work the wire teeth backward, out of the belt fabric. There is no such problem in the carding art, as the sheets of card clothing 15 are nailed upon a surface with which they travel and are subjected to no bending action in use.

The wire teeth are ground to a sharp edge, after being set in the belt fabric, by 20 means of an emery covered roller set in light contact with the teeth and rotated and reciprocated as the belt is also actuated, until the required sharp point is achieved. While in this specification the term "needle 25 point" is used, it is not strictly correct, since the result of the grinding process is a somewhat flat V-shaped edge, pointing in the direction of movement of the tooth in use.

At the inside of the front of the machine 30 upon the cross and side frame members, are secured the various mechanical elements which jointly and severally cooperate with the belt element in performing the necessary operations upon the seed cotton.

35 Referring now particularly to Figs. 2 and 3, it will be noted that three conveyors 17, 18 and 19 are placed across the machine and carried in suitable bearings, at their respective ends. The upper conveyor 17 includes 40 right and left sections for conveying the cotton to each side of the machine in the trough 20 of said conveyor. The conveyor 17 extends to each side, passing outside the frame. From each end of the trough 20 flues 21 45 extend downwardly on each side of the frame and discharge cotton into the ends of the trough 21 of the conveyor 18. The central portion of the bottom of the trough 221 is cut away at 22 so as to discharge the cotton therefrom. The conveyor 18 has its end 50 sections traveling over the closed bottoms of the trough so as to carry the seed cotton to the opening 22 and discharge onto the central belts, the marginal belts being beyond 55 the ends of the said opening 22.

On the conveyor shaft 23 are mounted agitators or beaters 24, which prevent the cotton choking the opening 22. It is pointed out that while cotton may be discharged 60 downwardly through the opening 22, it is also carried upwardly through said opening by reason of the upwardly traveling belts.

The entire front of the frame 10 has a 65 cover or front 25 preferably formed of sheet metal and braced by crossbars 26. Portions

of the cover are made into doors 27, 28, 29 and 30, respectively, hinged to swing outwardly and upwardly, whereby access may be had to the top of the machine, the central and bottom portions. At the location of the 70 conveyor 17 a feed opening 31 is provided in the cover. This opening does not extend the full width of the belts 11 and thus seed cotton is not fed onto the marginal belts. A hopper 32 is mounted contiguous to the 75 feed opening. Seed cotton, in the form of picked cotton, bollies and snaps, is fed from a boll breaker or any other form of machine desirable, to the hopper 32.

80 Mounted in the frame of the machine transversely, are a plurality of chutes 33, 34, 35 and 36, respectively, each inclining downwardly from the cover 25 toward the belts. Slidably mounted on the under side of the lower portion of each chute is a chute 85 apron 37 extending to a line adjacent the belts. Each apron has rack bars 38 on its under side engaged by pinions 39 on transverse shafts 40.

90 By adjusting the aprons toward and from the belts, the widths of the openings therebetween are regulated. The shafts 40 project outside the frame and carry small hand wheels 41 and locking nuts 42, whereby the shafts may be adjusted from the outside of the machine and locked in their adjusted positions, the operator observing through the glass covered ports 25' or by opening the doors. By this means the aprons may 95 be set as is desired.

100 Under the aprons 37 of the chutes 33, 35 and 36 transverse picker rolls 43, 143 and 243 are mounted and these rolls may be of any suitable construction including a plurality of pins projecting from a cylinder. Above the conveyor 17 a transverse rotary brush or doffer roller 44 is mounted so as to rotate in close proximity to the needle points of the belt. Above the roller 44 a transverse picker roll 45 is mounted adjacent the 105 front reach of the belt.

110 Between the rollers 44 and 45 I provide an inclined chute 46 of any suitable material and inclined downwardly from the belts so as to discharge material into the trough 20 of the conveyor 17 below. A large rotary brush or stripper 47 is mounted transversely above the upper end of the belt and just over the roller 13. This brush is housed within a hood 48. The hulls and other foreign matter finally find their way to the trough 49 in which the conveyor 19 travels.

115 The operation is as follows: The crushed and opened bolls bearing the seed cotton are delivered to the hopper 32 and ride down the bottom thereof onto the inclined chute 33 and its apron 37. As the mass of seed cotton and hulls enters the machine and slides down the chute it is shot against the belts 11. The needle point teeth of the 120

belts will pick up the lint and some of the broken bolls and the like adhering thereto will be carried upwardly by said belts. The teeth being very closely related will neither engage the hulls, nor can the hulls easily enter therebetween or be impaled thereon.

Lint cotton with any adhering hulls is carried upward past the trough 20 and the rotary brush 44 rotating as indicated by the 10 arrow brushes the hulls and most of the material not engaged by the belts so that the same falls into the trough 20. This brushing action is rather important as it has a tendency to comb the lint and thus straighten out the fibres.

Material carried beyond the brush 44 encounters the picker roll 45, by which all still adhering hulls and lint not belt-engaged are knocked onto the chute 46 and so delivered by gravity to the trough 20. The adhering lint is carried with the belt over the top roller 13 to the discharge chute 50, the brush 47 acting to brush the lint from the needle points of the belt into said chute.

25 The material delivered to the conveyor 17 will be carried to each end of the trough 20 and discharged into the flues 21 outside of the frame. This material is delivered by the flues to the extending ends of the trough 221. The conveyors 18 in this trough carry the material inwardly and discharge it through the opening 22 onto the belts 11 and the underlying chute 35. The agitators 24 will prevent a mass of seed cotton and hulls collecting below the trough 21 and within the trough.

40 All hulls and seed cotton not carried upward from the chute 33 will work downward between the belts 11 and the apron of the chute 33. This falling material will be engaged by the roller 43 and thrown against the belts. Such material as is picked up by the teeth of the belts will slide down the chute 34 and mix with the material discharged from the conveyor 18.

45 It is obvious that the material discharged from the trough 21 and that passing downward from the chute 34 will have a larger proportion of hulls, and such hulls and the 50 lint which has been picked up by the belts will slide down the chute 35 and fall between the apron thereof and the belts where it will be subjected to the action of the roller 143, the remaining material passing down the chute 36 and being thrown against the belts by the picker roller 243.

55 By the time the material has passed below the chute 36 and been acted upon by the roller 243, substantially all of the lint will 60 have been removed, thus leaving the rejected hulls and trash to fall into the trough 49 of the conveyor 19. At the end of these repeated operations the lint is separated, shaken and beaten free from hulls and trash,

the freed fibre ascending with the belts and 65 the rejected material descending to a lower level for another operation, until finally the rejected material, consisting of hulls and trash, is discharged into the conveyor 23.

It will be apparent that in a very real 70 sense the machine is made up of an upper mechanism having a feed hopper 32, an upper exit 50 and lower exits from the trough 20 through the chutes 21, whereby a portion of the entering material is passed 75 to the conveyor 18 which feeds the material across the machine and causes it to undergo a series of operations to enable the belts 11 to gather and convey to the upper exit 50 all clean lint.

80 It is pointed out that material entering through the opening 31 by way of hopper 32 is delivered only to the central belts, thus leaving the marginal belts free to handle cotton which is discharged below the chute 33 and the conveyor 18. The conveyor 17 carries the cotton to each side of the machine and thus provides an even distribution. The opening 22 in the trough 21 terminates short of the marginal belts, thus 85 leaving the same free to handle the cotton and hulls both above and below said trough 21.

90 Continued working of this machine has shown that excellent results are had by running snaps and bollies, as well as picked cotton, through the same. On hilly cotton the separation of hulls and cotton is nearly 95 perfect and it is possible to put a bale of very rough, bolly cotton through the machine with a loss of less than a pound of lint. An important point is that the teeth of the belts do not take hold or engage the hulls at any time, but instead engage the 100 lint and pick it from the hulls. For this reason the machine does not cut the hulls or put shale into the lint. Cotton treated by this machine is much improved and its value 105 is enhanced.

110 In Figs. 7 and 8 I have shown diagrammatic views setting forth the outside belt drive or layout on each side of the machine. In order that the driving of the parts may be more easily traced the same numerals have been applied to the outside driving 115 pulleys as are used to designate the interior parts driven thereby. As an illustration the two outside pulleys mounted on the shaft 12 carrying the upper inside pulleys 13 have been numbered "13" as forming part 120 of the assembly and so on throughout said figures. The outside pulley 13 in Fig. 7 is belted to a suitable source of drive. The direction of movement of the belts is indicated by arrows in Figs. 1, 3, 7 and 8.

125 The advantage of a plurality of picker belts over a single wide belt is manifest. A single wide belt is expensive and if one part

is worn, the entire belt must be replaced. Any of the several belts may be replaced and are longer lived than a single belt.

It has been found advantageous under some conditions to omit the fabric sheet 1^{xx} from the belts. The wire teeth 1^x being made in the form of staples and punched through the belt from the back side and remain in place, because even should they tend to work from the back of the belt, they would be driven into the belt when passing over the inside pulleys 13 and 14 and also when pressing against the support 16. The invention contemplates either the use of the back sheet or its omission.

Various changes in the size and shape of the different parts, as well as modifications and alterations, may be made within the scope of the appended claims.

20 What I claim, is:

1. In a cotton huller and opener, a supporting frame, an endless toothed picker belt, upper and lower supports over which the belt travels, the front reach of said belt traveling upwardly, means to doff lint from the belt at its upper portion, means for feeding cotton to the belt intermediate its supports, a multiplicity of beater rolls adjacent the front reach of the belt in spaced order, means for receiving and conveying cotton elevated by the belt above the feeding means and not adhering to the belt, said means distributing said cotton to each side of the machine, and means receiving said distributed cotton and conveying it from each side of the machine and discharging it onto the belt below the feeding means, whereby an equal lateral distribution of the cotton is had.
2. As in claim 1, the last named distributing and conveying means discharging the cotton on the central portion of the belt only, whereby the marginal portions of the belt are left free for other work.

3. As in claim 1, with a brushing roller above the first named receiving and conveying means for combing and brushing the lint.

4. In a cotton hull separator and opener, a frame casing having upper and lower cotton feed openings and upper and lower cotton exit openings, a traveling toothed picker belt supported on upper and lower supports within the casing, the inner reach of the belt moving upward to a lint exit opening; a chute adjacent the upper feed opening to receive the entering material and shoot it against the upwardly moving belt; a knocker roller adjacent the upper part of the upwardly moving belt, to beat back hulls and loose material while permitting the belt-engaged lint to pass on; means to remove the lint from the belt; a trough below the knocker roll to receive the material beaten back; a conveyor within the trough

to move said material in opposite directions along the trough to lower cotton exits at each side of the casing; a second conveyor below said exits to receive the descending material and return it within the casing through the lower feed opening; a chute over which the conveyor moves the material and down which it is guided against the toothed belt.

5. In a cotton hull separator and opener, 75 a frame casing having a feed opening and a lint exit opening; a traveling belt clothed with needle pointed wire teeth, supported on upper and lower supports, the inner face of the belt moving upward to the lint exit 80 opening; a chute adjacent the feed opening to receive the material and shoot it against the upwardly moving belt, a knocker roller adjacent the upper part of the upwardly moving belt, to beat back hulls and loose material, while permitting the belt-engaged 85 lint to pass on; a rotary brush located between the feed opening and the knocker roller for knocking off the hulls and at the same time brushing the lint elevated by the belt, and means to remove the lint from the wire teeth.

6. In a duplex cotton hull separator and 90 opener, a frame casing having a cotton inlet opening in its front side into an intermediate inlet feed compartment; an upper compartment above the inlet feed compartment; a knocker roller in said upper compartment; a lower compartment below said feed compartment; a beater roller in said lower compartment; by-passes at each side of the casing from the upper compartment to the lower compartment; means to move the material from the central portion of the upper compartment to each side to the by-passes; means to move the material from the by-passes at each side toward the central portion of the lower compartment; a toothed belt, one face of which moves upwardly 95 through the lower, intermediate and upper compartments, forming one wall thereof.

7. In a cotton hull separator and opener, 100 a frame casing having an upper feed opening and an upper lint exit opening; a toothed picker belt supported for travel on upper and lower supports within the casing, the inner face of the belt moving upward to the upper lint exit opening; a lower exit opening and a lower feed opening; a multiplicity of beater rolls adjacent the belt spaced one above the other; chutes arranged 105 below the several rollers coating therewith to guide and sustain the material for the action of the belt and beater rolls, adjustable aprons contiguous to the chutes and movable toward and from the belt, to vary the opening between the inner end of the chute and the face of the belt.

8. As in claim 7, means connected with 110 the aprons of the several chutes for adjust-

ing said chutes from the outside of the casing, and means for locking said adjusting means in position.

9. In a cotton hull separator and opener, 5 a supporting casing having an intermediate feed compartment provided with an inlet opening; an upper compartment above the inlet feed compartment; a lower compartment below the feed compartment; beater 10 rollers in the upper and lower compartments; a by-pass from the upper compartment to the lower compartment; means to move the material from the upper compartment to the by-pass; means to move the 15 material from the by-pass into the machine, and a plurality of vertical toothed belts intimately related with their edges contiguous, the front faces of the belts moving upward through the said compartments and 20 forming one wall thereof.

10. In a cotton hull separator and opener, a casing, a plurality of cotton treating compartments having communication with each other, an upright transverse support contiguous to one side of said compartments, and a plurality of endless toothed belts traveling vertically on the face of the support in parallel order and upwardly through said compartments for elevating the cotton 25 from one compartment to another, each of said belts being independently removable.

11. As in claim 10, upper and lower supports for said belts, and means on said supports for guiding and separating said belts to a minimum spacing, whereby hulls and cotton are prevented passing between the belts.

12. In a cotton hull separator and opener, 40 a casing having an intermediate feed compartment provided with a cotton feed inlet; an upper compartment above the feed compartment, a transverse conveyor trough separating the upper compartment from the feed compartment, a lower compartment below the feed compartment, by-passes outside the casing depending from the ends of the trough, a conveyor in the trough including right and left sections for conveying material to each end of the trough and discharging it into said by-passes, means entering the lower compartment from each side receiving material from the by-passes and discharging it into the lower compartment, 45 an endless picker belt traveling vertically through said compartments and picking

cotton from each compartment and elevating it, and means at the top of the casing for doffing the cotton from the belt.

13. As in claim 12, with beaters in the upper and lower compartments for casting 60 the cotton against the belt, and a brushing roller in the upper compartment for brushing the cotton adhering to the belt.

14. In a cotton hull separator and opener, 65 a casing having an intermediate feed compartment provided with a cotton feed inlet; an upper compartment above the feed compartment, a transverse conveyor trough separating the upper compartment from the feed compartment, a lower compartment 70 below the feed compartment, by-passes outside the casing depending from the ends of the trough, a conveyor in the trough including right and left sections for conveying material to each end of the trough and discharging it into said by-passes, a second conveyor trough extending transversely through the lower compartment and having a portion intermediate its ends cut-away, 75 the by-passes discharging into the second trough, a conveyor in the second trough having right and left sections for conveying the material to the cut away central portion of the said trough, agitators connected with the conveyor and acting contiguous to the cut-away portion of the second trough, an endless picker belt traveling vertically through said compartments and picking cotton from each compartment and elevating it, and means at the top of the casing for 80 doffing the cotton from the belt.

15. In a cotton hull separator and opener, 85 an upright casing having an intermediate feed compartment provided with a feed compartment provided with a feed opening terminating short of each side of the casing, an upper compartment above the feed compartment, a lower compartment below the feed compartment, by-passes from the upper compartment to the lower compartment, and endless toothed belts traveling vertically through the compartments, the marginal belts traveling on each side of the feed opening of the feed compartment, 90 whereby inflowing cotton is delivered to the intermediate belts only and the marginal belts are reserved for subsequent picking of the cotton.

In testimony whereof I affix my signature.
WILLIAM L. HANCOCK.
